(57) **CLAIM**

The ornamental design for a nail brush, as shown and described.

DESCRIPTION

FIG. 1 is a top perspective view of a nail brush;

FIG. 2 is a bottom perspective view thereof;

FIG. 3 is a top plan view thereof;

FIG. 4 is a bottom plan view thereof;

FIG. 5 is a first side elevation view thereof;

FIG. 6 is a second side elevation view thereof;

FIG. 7 is a front elevation view thereof;

FIG. 8 is a rear elevation view thereof;

FIG. 9 is an enlarged perspective view of FIG. 1; and,

FIG. 10 is an enlarged perspective view of FIG. 2.

The broken lines shown in the drawings illustrate environmental structure of the article of manufacture, and form no part of the claimed design.
